CATHODE TUBE RECORDER FOR
CALCULATING MACHINES

James W. Bryce, Glen Ridge, N. J., assignor to
International Business Machines Corporation,
New York, N. Y., a corporation of New York

Application June 30, 1939, Serial No. 282,208

22 Claims. (Cl. 235—61.6)

Record controlled accounting machines of the types now in use usually comprise record handling mechanism, record analyzing devices, calculating devices and recording mechanism. The recording mechanism is sometimes used to list data derived from each record of a run and at other times is used to record only the results of calculations and at other times such recording mechanism is used to record a list of detail data together with result data derived from the calculating mechanism.

In all such machines high overall speed of operation is a desideratum. Quietness of operation is also demanded by users.

According to the present state of development of the art it is possible to handle and analyze records at very much higher speeds than the speed attained in commercial practice to-day. Accumulator development has also afforded accumulators which are capable of operating accurately at very much higher speeds than now generally used in commercial practice.

Recording mechanisms, however, as now commercially used, involve type elements such as bars or wheels, each of which is provided with a plurality of type characters. Furthermore, it is the customary practice in power actuated accounting machines to provide a separate type element for each column of data to be recorded. Such type elements all have to be individually differentially positioned or set and after an impression is taken therefrom the elements have to be restored to home position before they can be reset for succeeding printing operations. Such operations are necessarily time consuming. The weight of the moving type elements is considerable on account of the number of columns of data to be recorded and on account of the number of type characters on each element.

The foregoing factors all contribute to limit the possible maximum speed of operation of the recording mechanism. Paper handling mechanism and the impression taking devices are also of such nature that they tend to limit operating speed. Furthermore, in the operation of such machines the elements of the recording mechanism when in operation, are a source of considerable noise which is objectionable to users. Change of type characters in the present day commercial machine is also time consuming and costly.

While there has recently been intensive development in printing and recording mechanisms with an endeavor to lighten the parts, provide higher operating speed and more quiet opera-

tion, no recording mechanism has been devised to date which affords overall operating speed equal to that attained in commercial practice by existing calculating mechanism, card handling and analyzing mechanisms. Furthermore, the best of recording mechanisms have maximum operating speeds materially below those attainable with improved card handling and calculating mechanisms which are now available.

10 In short, at the present time in machine accounting operations which involve recording, it is always the printing mechanism which determines the upper limit of operating speed and in the present state of development in the art the related other mechanisms frequently have to be slowed down to accommodate the relatively slow recording mechanism.

The present invention has for one of its objects the provision of an improved record controlled accounting machine with improved and novel recording means which enable recording to be effected at higher speeds than heretofore.

A further object resides in the improvement of machines of this class and in the improvement of the recording mechanism of such machines to the general end that recording may be effected at even higher speeds than calculating speed.

A further object of the present invention resides in the provision of a relatively noiseless recording device for an accounting machine.

A further object of the present invention resides in the provision of a record making accounting machine wherein provision is made to wholly dispose with differentially movable and settable parts in the number or character representing means of the recording mechanism.

A further object of the present invention resides in the provision of an improved recording mechanism for an accounting machine wherein there is practically no upper limit to the number of characters which may be provided in any one columnar order.

A further object resides in the provision of a construction wherein the recording characters may be readily changed or increased or decreased in number for any given column.

A further object of the present invention resides in the provision of a novel visual indicator for affording a clear and brilliant reading of a total calculated by the machine.

A further object of the present invention resides in the provision of a record controlled calculating machine provided with a recording apparatus adapted for providing an extremely compact record of items and/or totals.

A further object of the present invention resides in the provision of means for tracing and recording a special alphabetical or other special character.

A further object of the present invention resides in the provision of a novel automatic brilliance control affording uniform brilliancy of the various characters irrespective of their length of outline.

Further and other objects of the present invention will be hereinafter set forth in the accompanying specification and claims and shown in the drawings which show by way of illustration a preferred embodiment and the principle thereof and what I now consider to be the best mode in which I have contemplated applying that principle. Other embodiments of the invention employing the same or equivalent principals may be used and structural changes made as desired by those skilled in the art without departing from the present invention and within the spirit of the appended claims.

In general the foregoing objects are attained by utilizing inertia free representing devices for manifesting the characters to be recorded and in effecting recording by photography. Generally the improved machine comprises a record handling mechanism adapted to operate quietly and at high speed. Such speed may be higher than present commercial practice. Record analyzing means of known type are also provided for deriving and interpreting data from each record. Calculating mechanisms such as, for example, accumulating mechanisms are provided which are controlled by the record analyzing mechanism. Such calculating mechanisms are adapted for operation at speeds corresponding to the record handling speed. The recording mechanism includes a photographic film recording device which photographs characters or images displayed upon a screen. The screen in turn receives the images from an inertia free image tracing device. Such device preferably comprises a plurality of cathode ray tubes. According to the preferred construction one tube is provided for each column of data to be recorded, but in the alternative one tube may be used for more than one column and individual controls within the envelope may be provided for each column. For controlling and determining the image tracing operation of the inertia free cathode tube character manifesting device, there are provided a set of pattern component emitters. A set of these emitters are provided, one for each different character that is to be displayed or recorded. Such pattern component emitters afford a source of deflecting voltage to control the movement of the tracing electronic beam of the cathode ray tubes. Each pattern component emitter includes an element which represents both components of a character. According to one embodiment the pattern component emitter is of photoelectric type. Alternatively other forms may be used such as devices controlling variable resistors, which afford voltage variations derived from a varying source of potential. Other forms may also be used. Selecting and connecting devices are provided which are controlled and brought into action either by the record analyzing devices or by the calculating mechanism. These devices select which pattern component emitter is to be effective and connect such emitter to a cathode ray tube in a particular column. The connecting devices are individual, one for each

column. Suitable controls are provided for bringing the photographic recorder into action. These controls effect exposure, film feed and the like.

5 In the drawings:

Fig. 11 is an inside elevational view of the photographic recording apparatus. The view is 35 taken substantially on line 11-11 of Fig. 9;

Fig. 12 is a detail sectional view of this apparatus, the section being taken substantially on line 12-12 of Fig. 11;

Fig. 13 is a timing diagram of cam contact 40 devices, etc. of the machine;

Fig. 14 is a top plan view of a pattern component emitter unit with portions of the top cover broken away to show the construction;

Fig. 15 is a detail sectional view of one of 45 the pattern component emitters, the section being taken on line 15-15 of Fig. 14;

Fig. 16 is an end elevational detail view taken substantially on line 16-16 of Fig. 15;

Fig. 17 shows a pattern component disk, the 50 particular disk being the one used for deriving components for representing the digit 7;

Fig. 17a is a graph of the digit 7 with various plotting points delineated thereon;

Fig. 17b shows the layout of the pattern disks 55 for the remaining digits including zero. Each disk is respectively numbered to show the digit character represented thereby;

Fig. 17c shows a pattern component emitter disk with modified track configurations for controlling forward and back tracing;

Figs. 18a, 18b, 18c and 18d taken together and arranged from left to right in the relation shown in Fig. 19, show the complete embodiment of the circuit diagram;

60 Figs. 18aa and 18cc show portions of the circuit diagram for a modified embodiment of the invention;

Fig. 19 shows the relation of the circuit sheets for the main embodiment;

Fig. 20 shows the relation of the circuit sheets for the modified embodiment wherein Fig. 18aa replaces Fig. 18a and wherein Fig. 18cc replaces Fig. 18c in the circuit diagram;

Fig. 21 is an enlarged detail of certain of the

circuit connections shown on Fig. 18aa, but on a larger scale;

Fig. 22 is a top plan view of a pattern component emitter which is used for the modified embodiment of the invention;

Fig. 23 is a detail view taken on line 23—23 of Fig. 22;

Fig. 24 is a detail view of a fragment of one of the commutators showing a pair of brushes cooperating therewith;

Fig. 25 is a detail view taken on line 25—25 of Fig. 22; and

Fig. 26 is another detail taken on line 26—26 of Fig. 22;

Fig. 27 is a commutator layout for the commutators of the device of Fig. 22;

Fig. 28 is a view showing an image disposed on one of the cathode ray tubes when the modified embodiment of pattern component emitters is employed;

Fig. 29 is a detail showing the layout of the figure 0 with plotting points delineated thereon;

Fig. 30 shows a diagram of another modified embodiment of the invention wherein provision is made for tracing an alphabetical or other special character; and

Fig. 31 is a view of an emitter disk for controlling the tracing of the special character.

Fig. 32 diagrammatically shows, in circuit form, the alternative type of electronic tracing and display device adaptable for a plurality of denominational orders or columns.

The tabulating machine to which the present invention is shown as applied, is generally of the type shown in the patent to Lake and Daly, No. 1,976,617, but modified in accordance with the patent to G. F. Daly, No. 2,126,621. It may be generally explained that with tabulating machines constructed according to the above mentioned Lake et al. patent, two driving motors are employed. One motor drives the card analyzing and accumulating section of the machine and the other motor is employed for resetting and total taking purposes. When such machines are modified according to the construction of the Daly patent, there is provided a single driving motor which is utilized for card feed, accumulator drive and total taking purposes. This modified arrangement requires a clutching device for interrupting card feeding operations without stopping the accumulating drive mechanism.

General organization of the machine

Fig. 1 shows the general relation of the units of the machine. At the left is the customary card feeding and analyzing mechanism. The center section of the machine includes three accumulators. To the right there is shown the novel recording unit with the photographic recording section and the inertia free image tracing devices for tracing the character to be recorded. Below the accumulators there is the customary plugboard and below the plugboard there is indicated a box which contains the various pattern component emitters.

For convenience in subsequent description corresponding reference letters will be used where possible to correspond with the reference numerals of like parts in the Daly patent.

Machine drive

Referring to Fig. 5a, the tabulating motor TM, through the usual belt and pulley connection, drives the customary ratchet of the main clutch shown in Fig. 2. When clutch magnet 117 is

energized, the shaft 6 is clutched up for drive by the tabulating motor TM. Shaft 6 through gearing generally designated 6a in Fig. 5a, drives the main drive shaft 44. Gears 61a on the main drive shaft drive gears 67, one of which is provided for each accumulator. Gear 67 through the shafting and gearing generally designated 67b drives the clutch shaft 53 of each accumulator.

Drive for resetting and for total recording

Shaft 44 near its right hand end is provided with a gear 44a which, through gearing designated 44b and 44c, drives a shaft 19. Fixed to shaft 19 is a gear 84 which drives a gear 83 which has clutch driving element 82 integral therewith. Gear 83 is freely rotatable upon a shaft 75. Shaft 75 has fixed to it the gear 74 and an arm 76 (see also Fig. 5) which carries a spring pressed clutch dog 77 normally held in the position shown in Fig. 5 by a latching arm 78 supported by armature shaft 79 of magnet armature 80. Energization of magnet 81 will release the dog 77 for engagement with the clutch driving element 82. The gear 74 provides the usual reset drive to main reset shaft 72. Gear 73 (Fig. 5a) corresponds with gear 278 of Fig. 26 of the Lake and Daly patent. For resetting each individual accumulator, gears 70 are provided to drive the index wheel shaft 69 of each accumulator unit.

From the foregoing it will be understood that reset will be effected in the customary manner on a total operation when totaling magnet 81 is energized.

The L cams are disposed on shaft 19. This same shaft 19 through gearing 91, 90 and 89 drives emitter drive shaft 85. Gearing driven by shaft 75 drives shaft 92 which in turn drives the P cams of the machine. Such P cams rotate through one complete revolution in two machine cycles. In this respect the present arrangement differs from the device of the Daly Patent No. 2,126,621 wherein the P cams make a complete revolution in one machine cycle.

Card feed drive

Main drive shaft 6 through a gear designated 12, drives a pair of gears 12a and 12b which are fixed upon a common shaft. Gear 12b in turn drives a gear 12c which meshes with gear 13 of the card feed unit (see Fig. 3).

Card feed and record analyzing mechanism

Referring to Fig. 3, the usual analyzing brushes are indicated at UB and LB and the record cards are successively advanced from the stack R by picker 9 to pairs of feed rolls 10 which serve to advance the cards past the upper and lower brushes UB and LB in succession. The various card feed rolls are gear driven in unison in the customary manner. From a main driving gear 11, freely mounted upon a shaft 8, sleeve 1 (see also Fig. 4) affords a driving connection from gear 11 to an arm 15 which carries a spring pressed clutching dog 16 normally held in the position shown in Fig. 3 by an armature latch 17 controlled by a card feed clutch magnet 18. Disposed between gear 11 and arm 15 there is a gear 13 and a clutch driving disk 14 freely rotatable upon the sleeve 1. Gear 13 has the drive connection previously described to gear 12c which in turn, through gears 12b, 12a and 12 receives drive from shaft 6.

Referring again to Fig. 3, energization of the clutch magnet 18 will trip dog 16 into engagement with the disk 14 and the card feeding mechanism

will cause cards to be advanced past the usual brushes UB and LB. Card feeding and analyzing operations will continue as long as magnet 18 remains energized. Such magnet is de-energized on total taking cycles and card feeding will not occur on such total taking cycles.

Reference may be had to the Lake and Daly patent for details of operation of the reset clutch mechanism shown in Fig. 5 and for details of operation of the main clutch mechanism shown in Fig. 2.

Accumulating mechanism

The present machine includes three accumulators. Each of these accumulators is of the form fully described in the Lake and Daly patent.

The mode of operation of elements of one order may, however, be briefly described as follows:

Referring to Fig. 10, shaft 53 has slidably mounted thereon, but keyed for rotation therewith a clutch element 54, one for each denominational order of the accumulator. 54 is provided with a groove which fits the short arm of a lever 55 pivoted as shown and provided with a block 56 normally held by armature latch 57 of adding magnet 58. Release spring 59 bears against the extremity of the longer arm of lever 55 and moves the same in a counterclockwise direction upon release of block 56 by armature 57. This movement will bring the clutching member 54 into engagement with cooperating teeth 60 integral with the gear 61, loosely mounted on shaft 53. Gear 61 when thus coupled to shaft 53 will rotate a gear 62 which meshes thereto and will displace the accumulator index wheel 63. The usual knockoff is provided. The rearward extremity of member 55 is adapted to be engaged by a finger 64 towards the end of the cycle for disengaging the clutch element 54 from teeth 60 and relatching block 56 on armature 57.

Briefly summarizing the adding operation, the magnet 58 may be energized at various points in the cycle of the machine, depending upon the location of a perforation in the column of a record card analyzed by the lower brushes LB. This energization may take place in response to a perforation in any of the index point positions from 9 to 0, inclusive. A perforation in the "9" index point position will trip the clutch element 54 nine steps before finger 64 is operated to declutch it and a perforation in the "1" index point position will trip the clutch element 54 one step before it is decluched by the finger 64. Each step of clutching engagement corresponds to a tenth of a revolution in the accumulator index wheel 63 so that a "9" hole will move it $\frac{1}{10}$ of a revolution and the "1" hole will move it $\frac{1}{10}$ of a revolution.

Readout mechanism

Also driven by gear 61 (Fig. 10) is a gear 65. Since the ratio of gears 65 and 62 is two to one, the former will turn through a half revolution for each revolution of the latter. Carried by and insulated from gear 65 are two pairs of brush assemblies. The 66 pair comprises two electrically connected brushes one of which cooperates successively with ten conducting segments 67 and the other of which cooperates with an arcuate main conducting strip 68. The 66a pair also comprises two electrically connected brushes, one cooperating successively with ten conducting segments 67a while the other brush of this pair cooperates with arcuate conducting strip 68a. The relationship of the parts is such that when the index wheel 63 is in its zero position, one of the

brushes 66 and 66a are in contact with the zero segments 67 and 67a and the other brushes are in contact respectively with the common strips 68 and 68a. Gear 65 drives through an idler gear 67a to a supplemental gear 65b. Gear 65b in turn carries a brush structure 66b similar to that previously described which traverses a set of conducting segments 67b and common strip 68b.

The positioning of the brushes 66, 66a, 66b with respect to the cooperating conducting segments, provides a readout mechanism for reading out amounts standing on the accumulator. As shown, a triple readout is provided. The triple readout from each order of the accumulator is provided for a purpose which will be subsequently described. The shaft 69 (Fig. 10), upon which the index wheels of an accumulator are loosely mounted, is slotted for cooperation with the customary spring pressed reset pawls (not shown) pivoted upon and carried upon the individual index wheels in such a manner that counterclockwise rotation of shaft 69 will drive the index wheels 63 forward to zero position during a single revolution of shaft 69. Reset drive for shaft 69 is provided for in the manner previously described.

Referring now to Fig. 6, the constantly running drive shaft 19, through gearing generally designated 90 and 91, drives a gear 89 which is fast to an emitter drive shaft 85. The emitter drive shaft drives the brush assemblies of three emitters of conventional construction. Such emitters are designated EM1, EM2, EM3.

Referring to Fig. 9, there are provided a number of cam contact devices generally designated P. These cam contact devices are operated by cams carried on a shaft 92 driven from the shaft 75. These P cam contact devices only function during total taking cycles. Other cam control led contact devices generally designated L are operated by cams driven by a constantly running shaft 19. Other cam contact devices generally designated F are shown in Fig. 3. These are operated from suitable cams on shaft 93. The symbol F indicates that the cam contact devices so designated are associated with the card feeding mechanism and are operative only when such card feeding mechanisms function. The timing relations of the various cam contact devices are shown in Fig. 13.

Cam recording unit

Referring now to Figs. 1, 6 and 9, at the right hand end of the machine, the frame parts 150 (see Fig. 9) afford support for a box-like housing 151. Within this housing and mounted on a cross member 152 are a plurality of cathode ray tubes which are disposed in a row. One of these tubes is marked "153" in Fig. 6. The screened ends of the cathode ray tubes project out of the box-like housing 151 as indicated in Fig. 9.

The side frames of the housing 151 are formed with luglike extension portions 154 which receive studs 155 which pivotally support a frame member 156. The frame member 156 normally by gravity assumes the full line position shown in Fig. 9, wherein the rear portion of the frame member abuts adjusting set screws 157. If desired, however, the frame member 156 can be swung to the dotted line position to permit direct viewing of the screen ends of the cathode ray tubes. The frame member 156 carries a light-tight funnel 158 which at its forward end extends to the back plate 159 of the camera device. The back plate 159 also carries a suitable lens and

shutter assembly generally designated 160. 161 designates the shutter trip lever.

Referring now to Figs. 11 and 12, suitably fixed to the back plate 159 is an assembly plate 162.

Referring now to Figs. 9 and 12, a stud 163 carried by plate 162 affords a support for a spool of film generally designated 164. Shafts 165 and 166 are provided on which are fastened film feed sprockets 167 and 168. Another shaft 169 affords a support for a take-up film spool 170. Shaft 165 has fast to it a ratchet 171 (see Fig. 12) and a driving gear 172. Driving gear 172 is geared to an intermediate gear 173 which in turn is geared to a gear 174 fixed on shaft 166. A suitable belt and pulley drive connection is provided from a pulley 175 fixed to shaft 166 to the take-up spool pulley 176, on shaft 169. Shaft 166 is slotted at this end to receive a winding key generally designated 177 in Fig. 12 and which is normally in restricted position as shown. Suitably carried by the assembly plate 162 is a shutter and film feed operating solenoid 180. The solenoid 180 when energized, is adapted to downwardly depress an actuating member 181 and trip the shutter member 161. 181 is spring restored as shown and upon restoring movement a pawl 182 actuates the film feed to advance a film a line space. A spring 183 may be used to prevent retrograde movement of ratchet 171.

Referring again to Fig. 9, within the camera housing there is provided a pivoted film lever 184 which is spring held in contact with the film supply roll. When the film is exhausted, member 184 swings clockwise to such an extent that contacts 185 which may be termed the "film lever contacts" open. The camera assembly is provided with a suitably removable housing or cover generally designated 186 in Fig. 12. The removable cover is held in the position on the back plate by means of a pair of knurled thumb screws 187. The film which is provided with the usual feeding sprocket holes and designated 188 in Fig. 11, passes under the first two of a pair of film guides designated 190, thence through a film gate generally designated 191 (see also Fig. 9), thence under another pair of film guides 192. The film guides 190 and 192 and the film gate 191 are suitably mounted on the assembly plate 162.

The operation of the camera will be readily understood. The camera is first loaded with the cover 186 removed. The cover is then replaced and then upon energization of 180 a section of film is exposed. Upon de-energization of 180, film feed is provided for a line space and a new section of unexposed film is brought to the film gate. When the film is exhausted, the film lever contacts open and the operation stops. The operator then depresses the wind-up key 177 and winds the remaining section of the film on to the take-up reel 170. The film may then be removed and the camera reloaded.

In the use of an accounting machine incorporating the present improvements, each roll of film, after exposure, would be removed from the recorder unit and then developed. After development, fixing and drying, printed enlargements of any desired size or length can be made as desired. Duplicate copies in any desired number can also be printed. Reversal film can be used if desired. The steps need not be further described as they are all well known.

At this point in the description and before describing the mechanical details of the pattern component emitters, it may be helpful to briefly explain some of the characteristics of a cathode

ray tube. A typical and suitable cathode ray tube is illustrated diagrammatically on the circuit diagram (Fig. 18c). Such a tube comprises an evacuated body into which extends a heater element 200. Such a heater element is supplied with current from a battery 200a (Fig. 18b) when switch 249a is closed. Associated with the heater element is a cathode 201 providing a source of electrons. Also within the evacuated body and disposed in order from left to right are a grid 202, an anode number "1" designated 203, an anode number "2" designated 204 and two pairs of deflector plates. The number "1" anode 203 and the "2" anode 204 receive biasing potential from a resistor 204a connected across a battery 204b. This arrangement is customary in cathode ray tube practice. The upper and lower vertical deflecting plates are respectively designated YU and YL and the horizontal deflecting plates are designated XL and XR, signifying left and right horizontal deflection. The right hand end of the cathode ray tube also comprises a fluorescent screened end 207. The "Y" deflector plates are placed above and below the center axis of the tube. The "X" deflector plates are disposed to the right and left of the center axis of the tube.

In the operation of the cathode ray tube with no potential applied to either set of plates, the stream of electrons will be emitted along the central axis of the tube and impinge on the fluorescent screen 207 at the center of the screen. This will illuminate a spot at the center of the tube. If, however, the potential on the horizontal and vertical deflecting plates is changed, the stream of electrons can be deflected either upwardly or downwardly or to the right or to the left or in combined resultant directions. Changing relative positive potential on the Y set of plates will bring the stream of electrons up or down and similarly changing the relative potential on the X plates will divert the stream of electrons alternatively to the right or left. By providing proper potential and proper changing potential over a period of time on both sets of plates any desired figure or character can be traced on the fluorescent screen 207. By repeatedly tracing a beam of electrons to the proper points or areas of the screen, an image may be produced which can be either visibly read or photographed. Cathode ray tubes are adapted to operate and deflect electron beams at extremely high frequency. They may be termed an "inertia free image tracing device."

Having generally described the characteristics of a cathode ray tube, there will now be described one manner of providing the deflecting voltages which control the movement of the tracing electron beam of the various tubes.

Referring again to Fig. 1, reference character 210 designates a box or housing which is at the bottom of the machine and which affords housing for the pattern component emitter assembly. This assembly comprises a driving motor 211 (Fig. 14) which by any suitable drive such as by the belt and pulley arrangement shown, is adapted to constantly rotate shafts such 212. Fixed at intervals along these shafts 212 are a series of pattern disks, one of which is designated 213 in Fig. 15. In a numerical machine as in the present embodiment ten of such disks 213 are provided. Each disk 213 is generally opaque, but is provided with two transparent tracks, one of which is designated 213X and the other of which is designated 213Y. For each disk 213

there is provided two sources of light. Each source of light preferably comprises a lamp 214 within a lamp box 215 together with a suitable set of lenses 216 and an apertured diaphragm 217 which is provided to direct and concentrate the light on and through the transparent tracks of the disk 218. As shown in Fig. 14, it will be noted that there are two light sources, etc., for each disk. One light source directs light to and through the 218X track and the other light source directs light through the 218Y track. On the opposite side of each disk are two photo-cells which are respectively designated 218X and 218Y.

If the width of one of the tracks 218X is varied at different angular positions around disk 218, different amounts of illumination may be allowed to pass to the photo-cell 218X upon rotation of the disk. This will vary the output of the circuit controlled by the particular photo-cell. The photo-cells act to cause more or less current to flow in their related circuits depending upon the amount of light which they receive.

Referring now to Figs. 17 and 17a, on Fig. 17a the outlines of the numeral 7 have been laid out. As shown, the number 7 has been divided up into a set of sections of equal length, this particular number being numbered from 1 to 31 inclusive.

Referring to Fig. 17a, it will be noted that in order to trace the electron beam for the upper horizontal part of the figure, the Y component voltage should be maintained constant while points 1 to 13 are traced. If the disk of Fig. 17 be examined and the 218Y track be traced from 1 to 13, it will be noted that the transparent track has a constant maximum width for all points from 1 to 13. Thereafter the tracing beam should be caused to both descend and move to the left. To cause descent of the beam there is a gradual diminution of the width of the Y track from point 13 back to point 31.

Referring now to the 218X track, the X component at point 1 is zero. But from this point to point 13, the X track gradually increases in width as indicated on the disk. From point 13 back to point 30, the X track progressively diminishes in width.

To determine the width of say the Y slot at any point 13, the Y ordinate distance between the zero line of Fig. 17a to the point designated 13 is measured. This distance is then multiplied by a constant and the resulting amount will give the width of the Y slot at the 13 point of the disk. The constant which is used, is the ratio of the maximum width of the Y slot at say the point 1 with respect to the maximum distance between the X axis and the point 13, which is the maximum Y ordinate. The maximum width of a slot is an arbitrary value dependent upon the circuit relations and characteristics of the photo-cell tubes which are used.

Fig. 17b shows the configurations of the tracks for the disks which are utilized for other digit characteristics. The various disks of Figs. 17 and 17b constitute pattern component emitters and if these disks are maintained in a state of rotation, it will be appreciated that they will progressively vary the X component voltages and the Y component voltages which are applied to the deflecting plates of the cathode ray tubes.

It may be further explained that a common set of pattern component emitters are utilized for all cathode ray tubes. In the illustrated embodiment only three orders of cathode ray tubes have

been shown in the viewing arrangement, but in practice it will be appreciated that more tubes can be employed depending upon the number of orders to be recorded.

5 It will be understood that two photo-cells are provided for each digit whose image is to be traced.

10 Amplifier circuits, preferably including electron discharge devices, may be employed under control of the photo-cells 218X and 218Y, etc. These are to produce variations in potential across the deflecting plates of the cathode ray tubes 153 in accordance with variations of light impressed on the photo-cells as will be understood by those familiar with the art.

15 A simple and convenient amplifier circuit for this purpose is illustrated in the drawing (Fig. 18a).

20 Referring, for example, to the photo-cell 218X, which is utilized to control the horizontal deflection of the cathode ray beam in the cathode ray tube 153, for setting up the character 0. The photo-cell is connected in series with a battery 220 and a resistor 221, whereby the difference of

25 potential across the resistor varies in accordance with the illumination of the photo-cell. The grid cathode circuit of a vacuum tube 222 conveniently biased negative at all times by the battery 223, includes a portion of the resistor 221, preliminarily adjustable by a contact 224 on the resistor. The plate cathode circuit of the tube 222 includes a B battery or other source of direct current 225 and a resistor 226 in series therewith intermediate the positive side of the battery 225

30 and the plate of the tube 222. For impressing a proper voltage across the horizontal deflecting plates XL and XR of the cathode ray tube 153, which are connected to the terminals 227 and 228 of the amplifier unit, a biasing network is conveniently provided, including a resistor 229 connected across a source of voltage preferably comprising the series connected batteries 230, 231. The conductor intermediate the batteries 230, 231 is also connected to a preliminarily adjustable contact 232 on the resistor 226 and the terminals 227, 228 are respectively connected to a preliminarily adjustable contact 233 on the resistor 229 and to the positive side of the battery 225 (i. e., the positive end of the resistor 226).

35 40 45 50 55 60 65 70 75 It will now be seen that if the photo-cell 218X receives no illumination or a predetermined minimum illumination, the grid of the tube 222 will have a predetermined maximum negative bias. The contact arms 224, 232 and 233 are conveniently so adjusted (in a manner which will be readily understood by those familiar with the art) that for this 0 or predetermined minimum illumination of the cell 218X the resulting maximum negative bias on the grid of the tube 222 will be such that the output voltage between the terminals 227 and 228 will maintain the electron beam at one side of its horizontal path of travel, viz., the left hand side in the apparatus illustrated. That is, although the contact arm 232 is negative with respect to the positive side of the battery 225, the biasing network including the resistor 229 imposes sufficient opposing voltage in the circuit of the deflector plates XL, XR, as to make the terminal 227 just sufficiently positive with respect to the terminal 228 to maintain the electron beam in its extreme left hand position. Now, as the illumination of the cell 218X increases, the negative bias on the grid of the tube 222 decreases,

resulting in an increase of plate current and a corresponding increase of the potential drop between the positive side of the battery 225 and the contact 232. As a result, the potential of terminal 227 becomes less positive with respect to the terminal 228; the adjustments of the contacts on the resistors being conveniently such that the potential between the terminals 227 and 228 becomes zero for an illumination of the photo-cell 218X which is intended to represent a positioning of the cathode beam at the middle of its horizontal path. Increase of the illumination beyond this point results in making the terminal 228 positive with respect to the terminal 227, until at the point of maximum illumination, the cathode beam is deflected to its extreme right hand position.

It will be understood that the amplifier and balancing circuits controlled by the photo-cell 218Y are conveniently identical with those hereinabove described for the cell 218X so that the vertical displacement of the cathode beam between plates YL and YU is obtained by a correspondingly similar variation of output potential between the terminals 235, 236, to which these plates are connected.

Since it will now be understood that the actual position of the cathode ray beam at any instant depends upon the controlling potentials applied to both sets of deflecting plates XL, XR and YL, YU, the position of the beam is directly controlled (through the instrumentality of the amplifier circuits described) by the amount of illumination respectively received by the photo-cells 218X, 218Y. Thus, as the illumination respectively received by these photo-cells varies during rotation of the pattern component emitter, the cathode ray beam traces a path to portray the particular digit character (in this case the character 0) represented by the particular pattern component emitter which controls the illumination of the photo-cells, that is, the tracks 213X and 213Y respectively provide a predetermined variation in the illumination of the photo-cells 218X and 218Y for each cycle of rotation of the emitter and the resultant of the corresponding variations in deflecting potential on the plates of the cathode ray tubes, causes the cathode ray beam to trace a path—in this case a path depicting the character 0, which is predetermined by the pattern component emitter.

The foregoing description has explained in detail one section of the amplifier unit with its connections to the photo-cells and to the output terminals of the amplifier for the Figure 0. It will be understood that the amplifier is arranged with a plurality of sections of identical construction and wiring. There are such additional sections for characters 1 to 9 inclusive. Such sections are indicated by correspondingly numbered boxes on Fig. 18a of the wiring diagram.

The circuits for supplying current to the lamps 124 for illuminating the photo-cells are not shown in the circuit diagram for the complete machine. These illuminating lamps can be conveniently wired in any suitable circuit to any source of current which may be the source of current for the machine or an independent source.

It will be appreciated that suitable current supply and proper circuits to the heater elements of the amplifier tubes 222 should be pro-

vided. These features are well known in the art and for clarity in the circuit diagram, such features are omitted.

The foregoing description has explained generally the manner of applying the deflecting voltages to the cathode ray tubes. Before describing in detail the circuit diagram of the machine and the operation in detail, it may be generally explained that for a listing operation, when amounts are to be derived from record cards of a run and listed, provision is made for selectively connecting the proper amplifier terminals corresponding to the digits in each order of the record to the set of cathode ray tubes. This is done under control of the analyzing devices which analyze the record card. On a total taking operation on the other hand, the proper amplifier terminals are connected to the cathode ray tubes under the control of the readouts which are positioned by the accumulator in which a total stands.

There is one further control which may be mentioned at this point and that is a control to provide uniformity of illumination for different digit characters having a different length of line. For example, the digit 1 has a line which is materially shorter than the digit 7 or the digit 8. Accordingly, if no supplementary control was provided the digit 1 would be more intensely illuminated on the cathode ray tube than the digit 7 or 8 for example. This is due to the fact that a digit on the cathode ray tube is traced once for each rotation of the pattern emitter disk and accordingly for the digit 1 the beam actually traverses a shorter path in the same length of time than the path traversed in tracing out the digit 7.

It will be assumed that it is desired to list by the apparatus, items derived from a set of pre-punched record cards which are placed in the supply magazine of the machine. The operation may also be described with the assumption that it is desired to record a total of each group of records.

To prepare the machine for such a type of operation, plug connections are established from the lower brush plug sockets 237 (Fig. 18d) for the columns of the items which are desired to be listed to the emitter plug sockets 238, 239 and 240 (Figs. 18c and 18b). To provide for proper group control plug connections will be established from the proper order upper brush plug sockets 241 to the proper 242 sockets and other plug connections will be made from the proper 243 sockets to the proper 237 sockets. Assuming that group control is to be on three columns, a plug connection will be made from 244 to 245 and switch 246 will be thrown to open position. To simplify the disclosure only three columns of cathode ray tubes have been disclosed. It is obvious that more columns could be provided if desired. The accumulator on the circuit diagram is shown with only three accumulator magnets, but more could be provided if the machine capacity was increased in the recording section. In order to record a three column total on the accumulator, all columns of the recording apparatus will have to be employed and it must therefore be assumed that only two columns of data is derived from the record if there is a carryover to the highest order of the accumulator or that no carryover beyond the highest order occurs if data is derived from all three orders of the record. The accumulator magnets 58 are plugged

by proper plug connections from sockets 237 to sockets 241.

For a listing operation switch 248 would be thrown to the list position as shown. Switch 118 (Fig. 18d) should be closed.

Main line switch 249 (Fig. 18d) is closed, supplying current to buses 250 and 251. The driving motor 211 (Fig. 18c) for the pattern impulse emitters 213 will be set in operation. Switch 249a is closed providing current supply to the heater elements 200 of the various cathode ray tubes. Such tubes are allowed to heat up before the machine operation is started. Relay R40 (Fig. 18d) is initially energized, since cam contacts L19 and P9 are closed at the beginning of operations. With relay R40 energized, relay contacts R40a are closed and reset magnet 81 is energized, since the L2 contacts are now closed. Reset key 110 is now depressed, energizing relay R30. Contacts R30a now closed, establish a circuit from line 251, through stop key contacts, through film lever contacts 185, through relay contacts R30a now closed, through R25, through the customary contacts 116, through the motor clutch magnets 117, to the other side of the line. When 117 energizes, contacts 116 open, bringing about the customary energization of relay R1 which, in turn closes contacts R1a and brings the tabulating motor TM into circuit. With the tabulating motor in operation the P and L cams rotate from the D position onward because reset magnet 81 is energized (see Fig. 5) and since the motor clutch magnet 117 is energized, a reset cycle now ensues and during the first machine cycle of the reset cycle contacts P9 open, de-energizing relay R40. During the second machine cycle of the reset cycle, contacts P7 close, energizing R43. The circuit is through P7, R43, the LCLb contacts, the UCLb contacts, back to line. A stick circuit for R43 is established through stick contacts R43a which shunt the cam contacts P7. The stick circuit extends from left side of line 250 through relay contacts R43a now closed, relay coil R43, card lever contacts LCLb and UCLb in the position shown, to the right hand side of line 251. A supplemental stick circuit is provided by cam contacts F2 and F3 which are in shunt with card lever contacts LCLb and UCLb in the position shown. At the end of the reset cycle upon opening of cam contacts L1 relay R25 is de-energized, causing de-energization of R1 and stopping the tabulating motor.

It may be mentioned that the card lever contact circuits have not yet been established. It may be mentioned that in the reset cycle P4 closes to prevent de-energization of R25 when L1 opens until the end of the reset cycle. Start key 119 is now depressed to energize R33 and R32, R40 being de-energized at this time. Energization of R33 closes contacts R33a and the tabulating motor TM is again connected in circuit. With R32 energized, relay contacts R32a are closed and relay R39 is energized through said contacts and the contacts R43c of relay R43 now energized. With relay R39 energized, relay contacts R39b are closed and a circuit is established to the card feed clutch magnet 18. The first card is now fed to the upper brushes. The holding circuit for R43 through the stick contacts R43a is maintained when cam contacts F3 open by virtue of the shunt circuit around F3 through LCLb and UCLb which are in the position shown. Near the end of this card feed cycle, contacts L1 open to again break the holding cir-

cuit for the TM motor. Shortly after the L1 contacts open, the card in the customary manner will close the 120 card lever to energize UCL. The start key is again depressed and the machine goes through a second card feed cycle just as described before. During this second card feed cycle, since UCL is energized, the UCLb contacts are shifted and since the customary auto-control contacts are not now closed, the opening of contacts F3 de-energizes R43. With R43 de-energized, contacts R43d are closed and upon closure of the L19 contacts relay R40 becomes energized. Energization of R40 closes the R40a contacts and energizes the 81 reset clutch magnet upon closure of contacts L2. A reset cycle then ensues. It may be mentioned that towards the end of the second card feed cycle just described, card lever contacts 122 close to energize LCL. Accordingly, contacts LCLd are closed during the reset cycle and upon closure of P13 relay R100 is energized. This relay is maintained energized through the P11 contacts. During the reset cycle relay R43 is energized upon closure of cam contacts P7. Energization of R43 opens contacts R43d and relay R40 remains de-energized, having become de-energized upon opening of P9. With relay R40 de-energized, relay contacts R40b are in the position shown and relay R32 becomes energized upon closure of cam contacts L3. With R32 energized, relay contacts R32a are closed and a pick-up circuit is established for relay R39, the circuit extending to line through the R43c contacts and the P9 contacts. With R39 energized, the R39b contacts close and upon closure of the L2 contacts the card feed clutch magnet 18 is energized. A regular tabulating and card feed cycle now ensues. The first card of the group is now traversed past the lower brushes LB in the usual way.

During the card feed of the card past the lower brushes the emitters EM1, EM2 and EM3 rotate in synchronism with the card. These emitters are in the nature of distributing switches to distribute the timed impulses derived through the perforation or perforations in the record card to a related one of a set of relays which are respectively designated U0 to U9, T0 to T9 and H0 to H9 (see Figs. 18b and 18c). In the above relay designation "U" signifies units, "T" signifies tens, and "H" signifies hundreds, referring to columnar orders. The suffix designation signifies the digit value of a particular relay.

Let it be assumed that an amount on a record card is say 46. When the 4th index point in the tens order passes the lower brush in that order, a circuit will be established from line 251 (Fig. 18d), through the card lever contacts 122, thence through the customary circuit breaker contacts L26, through F4, to the contact roll, thence through the brush and via the plug connection from the 237 socket in the tens order to the 239 socket (Fig. 18c). The emitter EM2 will be traversing the 4th spot at the time the 4 index point perforation is sensed by the lower brush and accordingly the T4 relay will be energized, the return circuit being back to line 250 from the relay coil. With such T4 relay energized, it is maintained energized by stick contacts T4a, the stick circuit going back to line through the L24 contacts. In the units order when the 6 index point traverses the lower brush, a circuit is established via the path previously traced to the contact roll through the brush in the units order through the plug connection from the units order socket 237 to socket 238 and the emitter distributor EM3

being on the 6 spot a circuit is established to energize the U6 relay in this order. This relay has similar stick contacts U6a and the relay remains energized after it is initially energized.

It may be here stated that the purpose of the U, T and H relays is to provide a means for retaining a card reading of an amount derived from a record card after the record card has traversed the brushes.

The relays once selectively energized during the card analyzing portion of the cycle retain their selected setting and thereafter selectively connect the related amplifier section or sections which are influenced by the related pattern component emitters to the cathode ray tubes in the proper orders. It may be further explained that these relays are adapted to connect a common amplifier section to several of the cathode ray tubes. For example, if the amount derived from the card was 44, instead of 46, the 4 section of the amplified unit would be connected to the cathode ray tubes for both the units and tens orders.

In lieu of relay retaining devices other setup devices could be utilized. The U, T and H relays in addition to having the stick contacts designated with a suffix *a*, are provided with additional contacts designated with the suffix *x*, *y* and *b*. These are normally open contacts which become closed when a related relay is energized. Since the amount of 46 is read from the card, the T4 and U6 relays are energized and the T4*x* and *y* contacts, U6*x* and *y* contacts and the T4*b* contacts and the U6*b* contacts are all closed. The general purpose of the *x* and *y* contacts is to connect the *x* and *y* component output terminals of the amplifier units to the related deflecting plates of the cathode ray tubes. The general purpose of the *b* contacts is to provide a brilliance control for the cathode ray tubes.

From the output terminals of the amplifier unit, i. e., 227, 228, 235, 236, etc., a set of *x* and *y* component output lines generally designated 260*x* and 260*y* extend to the related *x* and *y* relay output contacts (Figs. 18b and 18c). The 260*x* lines of which there are ten, connect to the 0*x* to 9*x* relay contacts and the 260*y* lines of which there are also ten, connect to the 0*y* to 9*y* relay contacts. Since relays T4 and U6 are energized, the T4*x* and U6*x* contacts are closed and a circuit is established from the 4 and 6 digit section of the amplifier unit through the above mentioned relay contacts to lines 262*x* and 261*x*. The *y* contacts of the relays establish contacts from the 6 and 4 digit terminals of the amplifier unit, through the *y* relay contacts to lines designated 271*y*, 272*y*. The 261*x* lines and the 271*y* lines extend to normally open front contacts of a relay generally designated J. When the J relay is energized, the 261*x* line is connected to the XL plate of the cathode ray tube 153 pertaining to the units order and the 271*y* line is connected to the YL plate of the units order cathode ray tube. Similar circuit relations are established to the YL and XL plates of the tens order cathode ray tube. The YU and XR plates of all of the cathode ray tubes are connected to a line 274 which extends to the 228, 236, etc., terminals of the amplifier unit. The common line is also grounded as indicated at 275 (Fig. 18a).

While the connections have been traced out for the units and tens orders there are also a set of lines 263*x* and 273*y* in the relay section which pertains to the hundreds order.

It may be mentioned here that the relay J is

energized following the entry portion of the cycle and at a time when photographic recording is to be effected of a listed item.

Before describing the manner in which the J relay is energized, the brilliance control which is effected by the *b* contacts will be described.

Brilliance control

- Referring to Fig. 18c, each cathode ray tube 10 has a brilliance control grid designated 202. This brilliance control grid is connected to a line 276 which, when relay J is energized, connects through the relay contacts to a line 277*b*. From this line a circuit is completed through the closed 15 *b* contact, viz., the U6*b* contact to one of the group of lines 278 up on one of the lines of the group which are generally designated 279 to one of the lines of the set 280. The various lines 280 connect to adjustable taps cooperating with a 20 resistor 281 which is in shunt relation around a battery or other source of potential 282. The positive end of the resistor 281 is connected to a line 283 which extends to the cathodes of all of the cathode ray tubes.
- 25 The above mentioned circuit makes the grid 202 more or less relatively negative with respect to the cathode 200 of each cathode ray tube. The amount of this negative bias is dependent upon the relative length of line in the letter which is to be depicted. For example, the letter 1 being a short letter, will require less brilliance than the letter 8 and will therefore have a greater negative bias when this letter is to be depicted.
- 30 The taps of the resistor 281 are adjusted to provide the proper negative bias for each letter. Similar brilliance control circuits are provided in the tens and hundreds orders and these need not be described since their general circuit relations are the same for the units order.
- 35 It is desirable that the electron discharge action of the cathode ray tubes be suppressed until such time when image tracing for recording or visual inspection is desired. For this purpose a high negative bias is applied to the grid 202 40 through a circuit which may be traced as follows for the units order tube. From grid 202, through the line 276, through the normally closed R29*a* contacts, to line 285 up via the extreme right hand line of the group of wires 279, and over via a 45 connecting wire 286 to the right hand end of the resistor 281. The R29*a* contacts remain closed until it is desired to record. When recording is to be effected, the R29*a* contacts are opened upon energization of R29. R29 is energized concurrently with relay J in the following manner. Since relay R100 is energized, contacts R100*b* 50 are closed and a circuit is established through switch 248 in the position shown, through relay J, through the L23 contacts, the P10 contacts, the R29 relay, the P14 contacts to the other side of the line. Shortly after the above circuit is established to energize relay R29 and relay J, cam contacts L25 close to energize shutter magnet 180. The camera device then operates and takes 55 a picture of the images which are being traced on the cathode ray tubes. In the particular example under consideration, images representative of 46 would be traced on the units and tens order tubes and such images would be recorded on the film.
- 60 The operations attendant upon the energization of R29 and relay J may be summarized as follows: With R29 energized, the R29*a* contacts are opened to remove the normal high negative 65 bias from the grids 202 of the various cathode

ray tubes. With relay J energized, its related contacts J_a and J_b shift from the position shown to connect one set of plates of the various cathode ray tubes to the relay selector circuits and to ultimately connect the amplifier sections in circuit and apply the proper tracing potential to the deflecting plates of the tubes. Also when relay J is energized, the J_c contacts shift and connect the proper brilliance control for the images which are to be traced as applied to the respective tubes. The action in the camera need not be re-described as it is sufficient to state that the shutter is actuated and subsequently film feed occurs.

Succeeding cycles follow for the following record cards of a group. In each case there is an exposure of the images on the screens of the tubes for each card. The operation continues until group control changes.

When a change in control occurs the shunt circuit afforded by the group control unit around contacts F₃ is broken. This in the usual manner brings about de-energization of relay R₄₃ and also causes operation of the card feeding mechanism to be interrupted. With relay R₄₃ de-energized, contacts R_{43d} reassume the position shown and a circuit is established through P₉ and L₁₉ to energize relay R₄₀. With relay R₄₀ energized, relay contacts R_{40a} close and reset clutch magnet 81 is energized so that a reset cycle ensues.

Before the accumulator is reset the amount standing in the accumulator must be read out and recorded. In the reset cycle upon closure of cam contacts P₁₂, relay R₂₉ is reenergized, cam contacts P₁₄ being now closed. At this time, however, relay J is de-energized since contacts P₁₀ are now open. With R₂₉ energized, the normal high negative bias on the grids 202 of the cathode ray tubes will be removed upon opening of contacts R_{29a}.

With J de-energized, the various relay contacts of J will be in the relation shown in the circuit diagram and the X_L and Y_L deflecting plates of the cathode ray tubes will be connected to the common strips 68 and 68a of the readout. The readout for each order will then connect such deflecting plates to the proper sections of the amplifier unit. Connection is effected through a supplemental set of lines which extend to the 260_x and 260_y lines. The common strip 68b of each readout connects to a line 290 which extends down through one of the normally closed J_c relay contacts of relay J and connects to line 276 and to grid 202. The conducting segments of this section of the readout are individually connected to the 280 group of lines and such supplemental readout section affords a brilliance control for the particular number represented by the readout setting.

Referring again to Fig. 18d, when contacts L₂₅ close shutter magnet 180 is energized to bring about a photographing recording operation for recording the total on the film. The circuit which is established when the L₂₅ contacts close is traced as follows: From left side of line 250, through L₂₅ now closed, magnet 180, key contacts in the position shown, cam contacts P₁₂, relay contacts R_{100b} to the other side of the line.

To distinctly mark out a total on the film, provision is made to afford supplemental film spacing after a total recording operation. This is provided for in the following manner.

During the second portion of the reset cycle, contacts P₁₅ close and establish a circuit to energize shutter magnet 180 upon closure of cam

contacts L₂₅. A further shutter action and film feed ensues but at the time of the shutter operation, relay R₂₉ is de-energized due to the opening of contact P₁₄. With R₂₉ de-energized as previously explained there is a high negative bias on the grids 202 so that no image is traced. This operation provides a blank space on the film which signifies that the preceding recorded amount is a total amount.

10 Last card conditions

As usual in tabulating machines, special controls are provided for the operations pertaining to the last card of a run. Briefly these may be summarized as follows: When the last card passes the upper brushes, relay UCL is de-energized. This, however, does not occur until cam contacts F₃ have opened and re-closed. Upon the next card feed cycle when the last card passes the lower brushes, the relay R₄₃ is de-energized upon the opening of cam contacts F₂ and F₃, the UCL_b front contacts being open and the LCL_b contacts also being open at this time.

LCL is ultimately de-energized, interrupting the circuit to clutch magnet 117 and de-energizing R₁ which interrupts the circuit to the tabulating motor TM.

The machine operation now stops and the last total has to be recorded by hand initiated reset operation. Upon a hand reset R₁₀₀ is maintained energized following the last card of a run. R₁₀₀ is maintained energized to afford current supply for R₂₉ and shutter magnet 180 and ultimately P₁₁ will open after printing of the last total and after an extra space of film to de-energize R₁₀₀.

Visual reading of a total

If at any time in the operation it is desired to visibly read the amount standing on the accumulator, the machine can be stopped by depressing the usual stop key, or the machine can be pre-set to stop at the end of a group. This operation is brought about by opening switch 118 (Fig. 18d). When a change in group control occurs, R₄₀ energizes opening contacts R_{40d} in the branch holding circuit for relay R₁. With R₁ de-energized upon opening of contacts L₁ with contacts R_{40d} open, contacts R_{1a} will open and interrupt the current supply to motor TM causing the machine to stop at the end of a group. The recording attachment is swung up in the manner previously explained to permit the screen ends of the cathode ray tubes to be directly viewed by the operator. The operator then depresses a supplemental hand viewing key 300 (Fig. 18d) which energizes R₂₉ and removes the high negative bias from the control grid. The images of the total amount are then traced on the screens of the cathode ray tubes under the control of the readout in the manner previously explained. With key 300 depressed, shutter magnet 180 will be maintained out of circuit.

If it is desired to record totals only without listing the list switch 248 can be shifted to "no list" position. This will prevent energization of relay J altogether.

Modified embodiment

In the embodiment of the invention which has just been described, the pattern component emitters were of a type which utilized photo-cells and an electronic type of amplifier unit. In lieu of such an arrangement of pattern component emitters and amplifiers wherein variations in de-

flecting voltages were provided by varying the amount of light directed to the photo-cells a different arrangement may be employed.

According to this modified embodiment, the pattern component emitters are of a resistance type. In this modified arrangement the varying component potentials which are applied to the deflecting plates are derived from a device which comprises a resistance in shunt with a source of potential and with means for taking off potential values from different points along the resistor. The means for taking off these different amounts of potential comprise a series of continuously rotating switching devices in the form of emitters. This modified unit will now be described.

Pattern component emitter driving motor 211 is replaced by motor 211M (see Fig. 22 and Fig. 18cc). This motor continuously drives two shafts similar to 212 and designated 212M. Each shaft carries and drives the brush assemblies of ten emitter units. The brush assemblies are designated 310 and 311 in Figs. 25 and 26. Each brush 310 traverses a set of conducting segments generally designated 312. Brush 311 traverses a common continuous conducting segment 313. Also driven by the shafts 212M are a number of commutator disks generally designated 314 in Figs. 22 and 23. Ten of such commutators are provided. Bearing on each commutator disk 14 are a pair of brushes 314a and when a conducting spot on the commutator comes under the pair of brushes a circuit is established from brush to brush (see Fig. 24). The commutators are laid out with conducting portions to establish circuit relations as shown in Fig. 27. In this diagram the dark portions indicate the time in the cycle of rotation of the commutators when a circuit is established through a pair of brushes bearing upon that particular commutator segment. The top line of this diagram represents, by a darkened portion, the time in a cycle when a circuit is made from a conducting spot of segment 312 through brush 310 and brush 311 to the common strip 313.

Two emitters are utilized for each character, one emitter derives potential for the X component and the other emitter derives potential for the Y component.

Referring to Fig. 21, the right hand emitter has its conducting segments 312 connected as shown to points of different potential along a resistance 315 and the left hand emitter has its conducting segments also tapped to the same resistance. Across the resistance 315 is a source of potential such as two batteries 316 and 317. The mid-point of the two batteries is connected by a line 318 to which is connected a line 319. The outgoing lines are indicated as 320x and 320y and such lines for the zero emitter connect to the related lines of the 260x and 260y set (Fig. 18b). Line 319 connects to line 214 which is connected to the common side of the deflecting plates.

The operation of the device will be readily understood. During rotation of the brush assemblies at successive points in the rotation of these assemblies, different amounts of potential are tapped off from the resistor 315. These potentials provide the proper deflecting voltages for tracing the related image.

The manner in which the tapped connections are established from emitter segment spots to the resistor to provide deflecting potentials for different figure characters will now be described.

Referring to Fig. 29, here the character 0 is

shown. The maximum height of the character is taken as the total effective length of the resistor 315 (i. e., between 0 and 4, Fig. 21). A resistor of equal length, say the total length of 4 as shown on Fig. 21, is laid out across the horizontal axis symmetrically with respect to the character. The character is then sub-divided into a number of equal spaces from point to point around its outline. The distance between the spaces is based on how close together it is desired to have the point images appear on the cathode ray screen. For the character 0 to provide proper spacing, 22 equal sub-divisions of length have been taken. Obviously, if more spaces were taken, the character would be delineated more clearly and accurately and if less were taken there would be a less clear delineation of the character.

Having divided the character into the spaces, 20 the point 2 is projected downwardly on the resistor 315 for the X components and the same point is projected horizontally to the diagrammatic resistor for the Y components. The same plotting procedure is followed for all other points 25 around the character. Having completed the plotting, the intercepting points on the diagrammatic Y and X resistors are scaled off. Point 1 on the X resistor is a distance of .5 from the left hand end of the resistor assuming the entire 30 length of the resistor to scale to 4.

Now referring to Fig. 21, it will be noted that the first spot of the emitter for the X component is connected to the 0.5 tapped point of the resistor 315.

35 Considering now the Y component emitter to the left, the first point of the emitter is connected to the 2 tap on resistor 315 which is the center of the resistor having a length of 4. This procedure is followed for all of the following 40 points, further connections being established in succession for the various points around the outline of the character.

In Fig. 21, diagrammatic layouts have also been shown with connections for the numeral 1 and 45 the numeral 2. The numeral 1, it will be noted has all of the X components at a fixed point, viz., at the center tap 2.0 whereas the Y component tap connections progressively vary from one end of the resistor to the other end.

50 As explained before, the mid-point between the two batteries 316 and 317 connects through line 318, which connects through grounded line 214 (Fig. 18b) to the deflecting plates of the cathode ray tubes which are connected in common. These 55 are the XR and YU plates of the tubes. Now if the X tap at any instant be assumed to be at the extreme left of resistor 315, this will place a maximum positive potential upon the plate XL with respect to plate XR. On the other hand if the resistor tap at any instant be assumed to be at the extreme right hand end of the resistor, this will place the maximum negative potential on plate XL with respect to XR. Similar 60 relations will be set up for the Y component taps, that is, if the Y tap is at the extreme left end of the resistor there will be the maximum positive potential on YL with respect to YU and if the tap is at the far right hand end of the resistor, there will be the maximum negative potential on YL 65 with respect to YU.

Circuit diagram for modified embodiment

It may be explained that Fig. 21 shows the top 75 portion of Fig. 18aa, but on a larger scale in

order to more clearly show the emitter connection and resistance taps.

According to the modified form of the invention, Fig. 18aa replaces Fig. 18a. The lines from the pattern component emitters of resistor type connect to the 260x and 260y lines as shown and provide the desired X and Y potential values to these lines. Line 320x connects to the 260x line for the 0 character. Line 320y connects to the 260y line for the 0 character and so on for all of the different digits.

Fig. 18cc replaces Fig. 18c and in such replacement, commutator devices 314 constitute a means to provide a high negative bias on the grid as the pattern component emitter moves from one spot to the next in the intervening portion between spots when the brushes traverse the insulating portion of the pattern component emitter. These commutator devices also provide a means for completely extinguishing the beam between the end and starting point of each character. For instance, with the character 2 it is obviously not desired to trace any series of spots between the tail of the 2 and the beginning of the 2. It will be understood that with the modified embodiment that a character is traced by a series of spots (see Fig. 28). The duration of a spot image is the same for each spot, this being dependent upon the time that the pattern component emitter brushes are in contact with a conducting segment. The commutators cut off any tracing between the tail end of the 7 and the beginning of the top part of the 7 by applying high negative bias to the grids of the cathode ray tubes during that period of the cycle. In short, the commutators 314, one of which is provided for each digit and zero, time the application of high negative bias to the grids 202 of the respective cathode ray tubes. It will be noted that each commutator 314 has one brush connected in common to a line 325 which leads to the negative side of its battery 331. The other brush of each commutator 314 is connected to a point of a related resistor 330. The resistor 330 is in turn connected across a source of potential as, for example, the battery 331. The positive end of each resistor 330 is commonly connected to the line 283 which extends to the cathodes of the tubes 153. Each resistor 330 carries a variable connector 332 which is connected to the proper line of the 280 group. Summarizing, each commutator 314 has a resistor 330 and the connector 332 of each resistor connects to the line of group 280 which corresponds to the digit. The commutator provides control for certain of the 280 lines which ultimately extend to the grids 202 of tubes 153 when printing is being effected. When the brushes 314a of a commutator 314 are making contact, part of its resistor 330 is out of circuit and with its connector 332 properly adjusted there will be sufficient negative bias on its line 280 with respect to line 283 to prevent tracing of the electron beam on the screen. When the circuit through commutator 314 is open, however, the potential difference between the positive end of resistor 330 and connector 332 will be less since part of the battery potential is now taken care of by the unshunted portion of resistor 330. Accordingly, this new bias will be less negative and permit tracing of the electron beam on the screen.

A circuit is also provided from the negative side of one battery 331, via wire 286, to the R29a contacts.

In other respects the machine according to the modified embodiment functions in the manner previously described for the main embodiment.

The complete cycle of operations need not be traced. Essentially, the difference between the two embodiments is in the form of pattern component emitters which are used to provide deflecting voltage control and in the substitution of the commutator devices for the brilliancy control of the first described arrangement.

With the form of pattern component emitter shown in Figs. 17 and 17b, inclusive, the tracing beams were caused to follow a uni-directional path from the starting point upon a character to a finishing point, thereafter the tracing beam was re-directed to the starting point at extremely high speed and the character re-traced. With such form of pattern component emitter the configuration of the light track alone was used to cut off the tracing beam between the finishing point and the starting point. However, such emitters may be modified, if desired, to provide for a tracing beam which traces a character from the starting point to a finishing point and then re-traces the beam back along the character from the finishing point to the starting point over the same path, but in reverse direction. Such an arrangement is particularly adaptable for digital characters because of their simple configuration, since all digits and zero can be depicted with characters which each have a single starting and a single finishing point. This modified form of pattern component emitter is desirable because with such a form of emitter there is no faint image shown on the cathode ray tube between the finishing and starting point on open ended characters. With such a form of emitter it is unnecessary to use supplemental electrical controls to cut off the faint trace just mentioned. To provide for this bi-directional beam tracing operation the light tracks of the pattern component emitters shown in Figs. 17 and 17b would be arranged to direct the tracing beam from a starting point on a character to the finishing point in say the first 180 degrees of rotation of the disks, thereafter the configuration of the track would be reversed for the next 180 degrees of travel to bring the tracing beam back in a reverse direction over the path previously traced to the finishing point.

Fig. 17c shows a pattern component emitter for the digit 7 of this type. It will be noted that the Y track at starting point 1, assuming counterclockwise rotation of the disk, starts with a maximum width, remains at a maximum width to point 13 and then progressively diminishes in width to point 31. Such point 31 is 180 degrees from the starting point. The width then progressively increases for points 31, 30, 29, etc., back to point 13, at which point the track is again at maximum width. The track remains at maximum width back to the starting point 1.

Considering now the X track, at point 1, the track is of 0 width. From this point the track progressively increases in width to point 13. Thereafter it progressively decreases to point 31, which is 180 degrees from the starting point. From this point the track will progressively increase in width from points 31 back to 13. Thereafter the track will again progressively decrease back to point 1, the starting point.

With such an arrangement of pattern component emitters, all possible faint tracing beams between the finishing and starting points are eliminated.

It is also possible to modify the resistance type of pattern component emitters to provide for bi-directional tracing beams instead of the

uni-directional tracing beam as previously described. This merely involves the proper connection of the taps to the resistance for various successive points on the emitter and successive reversals of the connections when back tracking is desired.

According to the invention as previously described, total records on the film were indicated by supplemental spacing. However, with current accounting practice, it is the usual practice to indicate a total by a special symbol such as a star or by the letter T. The use of pattern component emitters lends itself particularly to the recording of such special alphabetical characters such as the letter T.

When it is desired to record such a character T in association with the total amount, it is only necessary to provide a special pattern component emitter with the proper configuration and arrangement to control the tracing of the T character. Fig. 31 shows such a form of emitter disk.

The emitter disk shown in Fig. 31 is associated with a suitable light source, photo-cell and amplifier unit generally designated T on Fig. 30.

Inasmuch as it may be desired to print the letter T in a selected column on the film, provision is made for connecting in the X and Y circuits from the T unit to a cathode ray tube in any selected order. To provide for the selective columnar printing of the letter T on the film, the circuit to the YL plate of the cathode ray tube in the units order is provided with two plug sockets 350 and 351 and the circuit to the XL plate is provided with two plug sockets 352, 353. These sockets are normally bridged by a plug connection. Similar plug sockets are provided for the tens, hundreds and thousands orders, such sockets being designated 354, 355 to 364, 365 inclusive. The circuits 276, to the negative biasing grid of each tube are similarly provided with sockets 366, 367, etc., to 372, 373. These plug sockets are normally completed by a plug jumper connection at each pair of sockets.

If it be desired to record the letter T in any order for example, assume the operator selects the thousands order, for the recording of the letter T, the plug connection between 362 and 363 is removed, the plug connection between 364 and 365 is removed and the plug connection between 372 and 373 is removed. Thereafter the operator of the machine establishes a plug connection between sockets 374x of the T amplifier unit to socket 364.

Another plug connection is established between socket 375y of the T amplifier unit to socket 362. These plug connections will afford proper tracing potentials for tracing the letter T in the cathode ray tube 153, pertaining to the thousands order.

A brilliance control circuit is established from socket 381 to socket 372 and a further plug connection is established from 376 to 380.

On a total cycle upon opening of cam contacts P16, such contacts remove high negative bias from the grid 202 of the thousands order tube and with this high negative bias removed, the character T is traced on the screen of the thousands order tube and thereafter photographically recorded along with the total.

It may be mentioned that the contacts R29a open at each listing cycle, but such open contacts are ineffective to remove the negative bias from the grid during listing cycles because such

open contacts are shunted by the P16 contacts during such listing cycles. On totaling, however, when R29a and P16 are concurrently open, high negative bias is removed and the proper brilliance potential is applied through the plug connection from 372 to 381.

Fig. 32 diagrammatically shows in plan view an alternative form of electronic tracing and display device of a known type now on the market. In the main form, the three sets of deflecting plates XL, XR, YU and YL are enclosed in three separate envelopes, one set for each column. In the alternative form, these three sets are replaced by similar sets X'L, X'R, Y'U and Y'L all enclosed in a single envelope 153' provided with a single display screen 207'. The units, tens and hundreds sets are transversely spaced to control tracing of characters in transverse disposition on the common screen. The circuit connections between the pattern component impulse emitters and the character selecting and control relays are the same for the alternative as for the main embodiment and are not completely shown in Fig. 32. Also, the connections between the total readout commutators and the electronic display devices are the same as in the main form and also are not completely shown in Fig. 32. In the alternative form, a single #1 anode 203' is used for all the sets of deflecting plates and this anode is connected to resistor 204a. Also, a single #2 anode 204' is common to the sets of deflector plates and is connected in the same manner as an anode 204 of Figs. 18b and 18c to the battery 204b. Further, anode 204' is connected through parallel leads to the three sets of deflector plates 1. The single heater element 200' is connected to the heater battery through switch 249a'. Three cathodes 201', one for each deflector plate set and similarly disposed, are provided. Also, three brilliance control grids 202' are used and connected in the same manner as in the main form. The operation of the deflector sets is controlled in the same manner as in the main form through the J relay contacts and contacts R29a into the component emitter selecting circuits and beam suppression circuits.

What is claimed is:

1. A record controlled character manifesting and displaying machine with record handling mechanism and including in combination, record analyzing means for analyzing the character representations on the records, a plurality of pattern component emitters one for each different character to be emitted and visibly manifested, each emitter generating component potentials required to control the tracing of its related character outline, a cathode ray tube for manifesting data derived from the records, pattern component emitter selecting and connecting means controlled by the analyzing means for selecting a pattern component emitter for action and for connecting the selected emitter to the cathode ray tube so that the tube may visibly manifest data derived from a record.
2. An image displaying mechanism including in combination, a cathode ray tube having a control grid, a plurality of image tracing control means for controlling the tracing of different images by said tube, a plurality of brilliance control means for impressing varying biasing control voltages on the control grid of the tube, and means comprising image selecting means to bring into action desired image tracing control means and their related brilliance control

means whereby each image traced will be of substantially the same brilliancy.

3. A record controlled character manifesting machine with record handling mechanism and including in combination, record analyzing means for analyzing character representations on a record, a cathode ray tube for tracing and manifesting character outlines on the screen thereof, a plurality of pattern component emitters, one for each different character to be emitted and manifested on the tube screen and each emitter generating the component tracing potentials required to control tracing of its related character outline by the tube, and pattern emitter selecting means controlled by the analyzing means according to the character representation analyzed thereby for selecting the related pattern component emitter for effective action and to cause the tracing potentials generated thereby to influence the cathode ray tube to manifest the related character upon the tube screen.

4. A record controlled character manifesting machine with record handling mechanism and including in combination, record analyzing means for analyzing character representations on a record, a cathode ray tube for manifesting character outlines on the screen thereof, a plurality of pattern component emitters, one for each different character to be emitted and manifested on the tube screen and each emitter generating the component potentials required to control tracing of its related character outline, means controlled by the analyzing means according to the character representation analyzed thereby for rendering the related one of the pattern component emitters effective to cause the potentials generated thereby to influence the cathode ray tube to distinctively manifest the related character upon the tube screen.

5. A numerical value character manifesting machine including in combination, variably and selectively settable value control means each setting of which corresponds to a different numerical value, means for selectively setting the value control means according to a desired numerical value, a cathode ray tube for tracing and impermanently manifesting different value character outlines on the screen thereof, a plurality of pattern component emitters, one for each different value outline to be traced and manifested on the tube screen and each emitter generating the component potentials required to control tracing of its related value outline, cyclically operable means, and means controlled by the value control means according to the setting thereof and by the cyclically operating means for causing the tube to display a numerical value under the control of the pattern component emitter related to the value represented by the setting of the control means.

6. A record controlled character manifesting and displaying machine with record handling mechanism and including in combination, record analyzing means for analyzing the character representation on the records, a plurality of pattern component emitters, one for each different character to be emitted and visibly manifested, each emitter generating component potentials required to control tracing of its related character outline, a cathode ray tube for visibly manifesting data corresponding to data derived from the records, cyclically operable means, means controlled by the record analyzing means and by the cyclically operable means for causing

the tube to visibly manifest a character under the control of the pattern component emitter related to the analyzed character representation.

7. A record controlled character manifesting machine, in which record handling mechanism is provided to handle, in succession, records bearing character representations, comprising in combination, analyzing means for analyzing each successive record for character representations, a plurality of pattern component emitters, one for each different character to be manifested, and each generating component voltages corresponding to the related character, a cathode ray tube responsive to the different component emitters according to the voltages generated thereby for tracing the different characters to be manifested, circuits for placing the pattern component emitters in control of the tube, and contact means conditioned under control of the analyzing means according to a character representation on an analyzed record for selectively controlling the circuits to place the pattern component emitter corresponding to the latter character in effective control of the tube.

8. A record controlled character manifesting machine with record handling mechanism to handle successive records bearing character representations, comprising analyzing means for analyzing each successive record for character representations, a plurality of pattern component emitters, one for each different character to be manifested and each generating component voltages corresponding to the related character, a cathode ray tube responsive to the component emitters according to voltages generated thereby for tracing the different characters, a plurality of circuit means, one for each different character to be traced, each said circuit means for operatively connecting one of the pattern component emitters to the cathode ray tube to cause the tube in response to the component voltages generated by said emitter to trace the related character, a plurality of normally open contact means, each such contact means being included in one of the circuit means, and each corresponding to one of the characters, means controlled by the analyzing means for selectively closing the contact means corresponding to the character on an analyzed record, means for holding the operated contact means in operated condition until after the character representations of the latter record have been analyzed, and means thereupon effective for causing the circuit means in which the operated contact means is included to establish tube operation in response to the component voltages generated by the emitter corresponding to the analyzed character.

9. A record controlled character manifesting machine with record handling mechanism and including in combination, record analyzing means for analyzing the character representations on the records, a plurality of pattern component emitters, one for each different character to be emitted and manifested, each emitter generating component potentials required to control the tracing of its related character outline, cathode ray tube means for manifesting data, said tube means having a screen on which character outlines are traced, pattern emitter selecting means controlled by the analyzing means for selecting the related pattern emitter for effective action corresponding to the represented character and for causing the selected pattern emitter by the component potentials generated thereby to influence the cathode ray tube means to manifest the character.

10. A displaying apparatus for displaying amounts calculated by a calculating machine, said calculating machine including a denominational order control element for representing an amount, said apparatus including in combination an electronic character displaying device for each denominational order and a plurality of pattern component emitters one for each different character to be emitted and manifested by the displaying device and each emitter generating component tracing potentials required to control tracing of its related character outline and selecting means controlled by the denominational order control element of the calculating machine for selecting the emitter to effectively control the action of the electronic device so that it displays a represented amount.

11. In a character manifesting apparatus, the combination of means providing images to be displayed, said means comprising in combination an electronic character displaying device, a plurality of pattern component emitters for generating component potentials required to control tracing of a plurality of different character outlines by the electronic device, pattern emitter selecting means for selecting the pattern component emitter for effective action, whereby the electronic device will display the character corresponding to the selected emitter, and means for controlling said selecting means to select any desired one of the emitters.

12. A record controlled accounting machine with record handling mechanism for handling the control records and including in combination, record analyzing means for analyzing numerical character representations on the records, calculating mechanism having result receiving means controlled by said analyzing means, a plurality of pattern component emitters one for each different digit to be recorded, each emitter generating component potentials required to control the tracing of its related character outline, a cathode ray tube for manifesting result data, pattern component emitter selecting means controlled by the aforesaid result receiving means for selecting a pattern component emitter for action and for connecting the selected emitter to the cathode ray tube so that the tube may manifest a result standing in the result receiving means.

13. A record controlled accounting machine for manifesting results and having record handling mechanism, and including in combination, a plurality of pattern component emitters one for each different digit to be manifested, each emitter generating the component potentials required to control tracing of its related character outline, record analyzing means for analyzing character representations on handled records, calculating means having result receiving means controlled by said analyzing means, cathode ray tube character outline manifesting means and pattern component emitter selecting and connecting means controlled by the aforesaid result receiving means for selecting an emitter for action and for connecting the selected emitter to the cathode ray tube means whereby the result may be manifested.

14. A calculating machine having, in a denominational order a control element and including in combination an electronic character tracing and displaying device, a plurality of pattern component emitters for generating the component potentials required to control the electronic displaying device to cause the latter to trace different

character outlines, connecting means controlled by the control element of the calculating machine and between the emitters and electronic device whereby said character tracing and displaying device derives generated component character tracing potentials from said selected emitter under control of the control element of the calculating machine.

15. A calculating machine having, in a denominational order, a control element and including in combination, a plurality of pattern component emitters for generating component potentials required to control tracing of different character outlines corresponding to amounts and represented by the control element, pattern emitter selecting means controlled by the control element of the calculating machine, and a cathode ray tube controlled for its displaying action by said selected emitter according to the potentials generated thereby.

16. A machine according to claim 4, wherein the cathode ray tube includes a brilliance control grid, brilliance control means for controlling the bias upon said grid and wherein the means controlled by the analyzing means for rendering the related pattern component emitter effective includes supplemental means for bringing brilliance control means into action to provide character display at substantially the same brilliance for each character.

17. A record controlled character manifesting machine with record handling mechanism and including in combination, record analyzing means for analyzing character representations on the records, a cathode ray tube for tracing different character images and including a control portion normally biased to suppress visible image manifestation, a plurality of pattern component emitters, each for controlling the tracing by the tube of a different character image, control means operable for causing reduction of bias on said control portion so as to render said portion ineffective to suppress visible image manifestation by the tube, and means controlled by the record analyzing means according to an analyzed character representation for selecting for conjoint action with the control means the particular emitter corresponding to the represented character whereby the related image will be visibly manifested by the tube to the exclusion of other images.

18. A record controlled character manifesting machine with record handling mechanism and including in combination, record analyzing means for analyzing character representations on the records, a cathode ray tube for tracing different characters, a plurality of pattern component emitters, each to control the tube to trace a different one of the characters, and means under control of the analyzing means for selectively operatingly connecting one of the emitters to the tube to control tracing thereby of the character related to the analyzed character representation.

19. A character manifesting machine including in combination, a cathode ray tube for tracing different character images on the screen thereof, a plurality of pattern component emitters, one for each different character image to be traced and each emitter controlling the tracing by the tube of a different character image, and means for operatively connecting any selected one of the pattern component emitters to the tube to control tracing of the related character image including cyclically operating means and character image selecting means conjointly effective to operatively connect a selected one of the emit-

ters to the tube to control tracing of the image of the selected character.

20. A machine for converting character designations on records into related graphic character representations and having record handling means, and including in combination, record analyzing means to analyze the records for character designations, a cathode ray tube for tracing and manifesting the characters to be graphically represented, a plurality of pattern component emitters corresponding to different character designations, each emitter to control the tube to trace a different one of the characters to be graphically represented, and means controlled by the analyzing means according to the analyzed character designation for selecting the corresponding emitter to control tracing by the tube of the related character to be graphically represented.

21. An image displaying mechanism including a plurality of pattern component emitters each for controlling the tracing of a different character image, a cathode ray tube with means selectively influenced by the emitters individually to trace the related characters, said tube including also a control grid, a plurality of brilliance control

means for impressing vary biasing control voltages on the control grid of the tube and means for selectively placing said cathode ray tube under control of a desired emitter and the corresponding brilliance control means, so as to cause each image traced to be of substantially equal brilliance.

22. A character manifesting machine comprising in combination, character selecting means, a cathode ray tube for tracing different character images and including a control portion normally biased to suppress visible image manifestation, a plurality of pattern component emitters, each for controlling the tracing by the tube of a different character image, control means operable for causing reduction of bias on said control portion so as to render said portion ineffective to suppress visible image manifestation by the tube, and means controlled by the character selecting means for selecting for conjoint action with the control means the particular emitter corresponding to the selected character whereby the related image will be visibly manifested by the tube to the exclusion of other images.
